UNITED STATES PATENT OFFICE.

SIDNEY C. ERLANGER, OF NEW YORK, N. Y., ASSIGNOR TO THE B. V. D. COMPANY, OF NEW YORK, N. Y., A CORPORATION OF DELAWARE.

GARMENT.

1,090,464.

Specification of Letters Patent. Patented Mar. 17, 1914.

Application filed November 13, 1911. Serial No. 659,989.

To all whom it may concern:

Be it known that I, SIDNEY C. ERLANGER, a citizen of the United States, and a resident of New York city, New York, have 5 invented certain new and useful Improvements in Garments, of which the following is a specification.

The present invention relates to the strengthening of elastic fabrics by means of 10 a reinforcement composed of similarly elastic fabric, so united as to contain the full benefits of the double thickness without sacrificing the required elasticity of the structure as a whole.

15 The invention is particularly adapted for use in connection with the manufacture of underwear. In order to have these garments properly fit the body of the wearer, the manufacturers frequently use an elastic 20 fabric such as webbing, as a part of the garment, the balance being composed of nainsook and jean or other suitable relatively inelastic fabric.

I have shown my invention as applied to 25 the elastic insertion at the back of the union suit. Experience has shown that this portion of the garment requires reinforcing. Heretofore, whenever it has been attempted to reinforce such an elastic knit structure, 30 it was customary to avoid the use of stitches passing through the active portions of the elastic fabric, since the stitches being composed of inelastic material, would render the entire portion of the elastic fabric traversed 35 by the stitches inelastic. Consequently, the stitching was entirely omitted in the elastic insertion except where it joined the inelastic fabric. Where stitches were used, it was at the expense of the elasticity of the fabric, 40 as explained, at the very point where the elasticity was desired. It was consequently considered impossible to unite two elastic fabrics by continuous stitching and leave the united fabrics the same degree of elasticity possessed by each component part 45 thereof.

I have now discovered that two elastic fabrics can be joined by stitches and yet retain their full elastic capacity. This result I obtain by uniting the two elastic fabrics by means of inelastic threads traveling in a zigzag direction over the entire elastic portion. In other words, the stitching instead of progressing from one aperture 50 through the fabric to another aperture in a

straight line, progresses from one aperture at the right to a second aperture slightly in front of it at the left, then back again to the right; then similarly advancing in a zigzag direction in this same fashion, thus 60 forming two parallel rows of perforations, the perforations in each row being located on lines drawn half way between the perforations of the other row. Elastic fabrics thus united, will, when stretched, increase 65 the intervals between the apertures of each row and as this stretching is not in the same direction as that taken at any point by the inelastic thread, this inelastic thread will, so to speak, pivot in each aperture and adjust itself without being subjected to the 70 tension of the stretch to the altered position of the aperture in the stretched fabric. This zig-zag stitch, the threads of which pass alternately from one hole to the other 75 of two parallel rows of needle holes, is employed within and in proximity to the edge of the reinforcing strip, but as shown in the drawings, distant from the end of the strip being reinforced. The individual stitches 80 composing the zig-zag threads all extend at an acute angle to the wales of the two ribbed elastic fabrics. In this way the two elastic fabrics are united by the use of thread 85 which in itself has no elasticity.

In the drawings, Figure 1 represents the rear portion of a union suit reinforced at the center of the back. Fig. 2 is an enlarged view showing one row of uniting stitches. Fig. 3 is the same as Fig. 2, showing the 90 fabrics stretched. Fig. 4 is the section through the line 4-4 of Fig. 2, showing how the two threads in each stitch interlock in each aperture.

The body portion of the union suit A is 95 made of relatively inelastic fabric. The insertion B is composed of a knit, ribbed, or other elastic fabric of a similar nature; at C this elastic fabric is reinforced by the use of a piece of elastic fabric of the same nature as that composing the insertion B. The two elastic parts are united by the stitches composed of threads D and E interlocking within the apertures F, as shown at G. Garments thus reinforced are just as elastic at 100 the point C, as at the adjacent parts H because the inelastic threads D and E can adjust themselves to the position of the fabric when stretched, as shown in Fig. 3. They do not impede or obstruct the full 110

elastic capacity of the united parts, provided the two united elastic fabrics are united in the direction of their elastic capacity, *i. e.* the two pieces of fabric should be superposed, or joined in such a way that the elasticity runs in the same directions.

It is one of the advantages of my improvement that the two superposed layers yield together, as described, without possibility of the formation of gathers or puckers due to the presence of the stitching. This result is obtained by placing the apertures through which the threads pass in parallel rows and carrying the thread always forward without "back stitching" and without overlapping of one stitch by another. This arrangement avoids any drawing forward of small portions of the fabric whereby puckers are formed.

20 What I claim is:

In a garment, an elastic, knit, ribbed fabric strip adapted to yield transversely of the ribs or wales, and a reinforcing strip of

similar material placed upon and adapted to partially cover the first named strip, the ribs or wales of said strip being parallel to the ribs or wales of the first named strip so that the two fabrics are yieldable in the same direction, such reinforcing strip being secured to the first strip by an elastic seam extending transversely of the ribs and composed of zig-zag stitching, the threads of which pass alternately from one hole to the other of two parallel rows of needle holes within and in proximity to the edge of said reinforcing strip but distant from the end of the strip being reinforced so that the individual stitches all extend at an acute angle to the wales of the two elastic fabrics.

In testimony whereof I have hereunto set my hand in the presence of two subscribing witnesses.

SIDNEY C. ERLANGER.
